UNITED STATES PATENT OFFICE.

RICHARD AYRTON ENGLAND AND HERBERT ROBERTS, OF BINGLEY,
ENGLAND.

CLOTH-CUTTING OR LIKE MACHINE.

SPECIFICATION forming part of Letters Patent No. 668,632, dated February 26, 1901.

Application filed September 14, 1900. Serial No. 30,028. (No model.)

To all whom it may concern:

Be it known that we, RICHARD AYRTON ENGLAND and HERBERT ROBERTS, subjects of the Queen of Great Britain and Ireland, residing at Bingley, in the county of York, England, have invented new and useful Improvements in Cloth-Cutting or Like Machines, of which the following is a specification.

Our invention relates to cloth-cutting and like machines, the object being to provide an appliance for taking up the slack edges of the fabric or adjusting the tension of the said fabric at any desired part. For this purpose we employ a counter-shaft mounted in any suitable manner over the draw-roller and suitably driven from any desired part of the machine. On this shaft are mounted two or more friction-rollers, which are adjustable as to their position on the shaft, so as to be adaptable for various widths of cloth, and are preferably covered with steel carding. The speed of the said counter-shaft may also be varied (according to the condition of the fabric under treatment) by means of suitable cone-pulleys.

In the accompanying drawings, Figure 1 is a partial end elevation of a cloth-cutting machine having our improvements applied. Fig. 2 is a sectional end elevation of a cloth-cutting machine, showing such parts as are necessary to illustrate our invention. Fig. 3 is a front elevation of the friction-roller shaft and its bearings, one of the said friction-rollers being shown in section.

A is the counter-shaft, which is suspended over the draw-roller B by adjustable arms C from the frame D. On the said shaft A are mounted the friction-rollers E, preferably covered with steel carding F and adjusted by studs G. The said shaft A also carries a cone-pulley H, which is preferably driven from the draw-roller B by means of belts P J and intermediate shaft K with cone-pulley R; but the shaft A may be driven in any other ap-

proved manner, so that the friction-rollers and the draw-roller are revolved at different surface speeds. The belt P is a crossed belt, and the belt J is an open belt, so that the rollers E are revolved in the reverse direction from the roller B.

L is a shaft, and M represents toothed wheels which are part of mechanism for adjusting the tension of the belt J, but which is not herein fully described or shown, as it is not an essential part of the present invention.

S is a guide-roller for bending the cloth partially around the roller B.

The edges or lists of the fabric N on passing between the draw-roller B and the adjustable friction-rollers E are thus tightened to any required degree, according to the speed at which the counter-shaft A is run. By this means a perfectly even tension of the fabric at all parts may be obtained and the fabric is rendered less liable to being damaged during the cutting operation.

What we claim as our invention, and desire to secure by Letters Patent, is—

In apparatus for equalizing the tension on textile fabric, the combination, with a draw-roller B, and a guide-roller S which bends the fabric partially around the draw-roller; of a counter-shaft A, adjustable arms C C provided with bearings for the counter-shaft, adjustable friction-rollers E secured on the counter-shaft at points opposite to where the tension of the fabric is to be changed, and driving devices for revolving the said draw-roller and the friction-rollers at different surface speeds, substantially as set forth.

In testimony whereof we have signed our names to this specification in the presence of two subscribing witnesses.

RICHARD AYRTON ENGLAND.
HERBERT ROBERTS.
